FIG. 1 is a perspective view of a portable illuminated sign embodying the present design;

FIG. 2 is a top plan view of the sign shown in FIG. 1;

FIG. 3 is a bottom plan view of the sign shown in FIGS. 1 and 2;

FIG. 4 is a front elevational view of the sign shown in the preceding figures;

FIG. 5 is an elevational view of the side opposite that shown in FIG. 1;

FIG. 6 is a rear elevational view; and

FIG. 7 is a vertical cross sectional view of a panel on the front of the sign, the section being taken on line 7-7 of FIG. 4.

The lettering on the face of the sign is for illustrative purposes only and does not constitute a part of the novel design.

The switch elements are omitted from FIGS. 2 and 3 for ease of illustration.

I claim:

The ornamental design for a portable illuminated sign, substantially as shown and described.
